JACK

Adolph J. Ricker, South Milwaukee, Wis., assignor to Badger Malleable & Mfg. Company, South Milwaukee, Wis., a corporation of Wisconsin

Application May 5, 1938, Serial No. 206,159

5 Claims. (Cl. 254—111)

This invention relates to improvements in jacks.

It is the object of the invention to provide a jack suitable for use in connection with tractors and other vehicles and for other purposes wherein a long lever is provided to enable the jack to be operated at a point well beneath the body of the vehicle, a control for the holding pawl being extended along the handle to the position normally occupied by the operator's hand so that the holding pawl may conveniently and safely be retracted when it is desired to lower the jack.

Further objects of the invention include the provision and means for achieving the above purposes safely, simply, and economically, as will appear more fully from the disclosure of the following specification and drawing.

In the drawing:

Figure 1 is a view partially in side elevation and partially broken away to a longitudinal section to expose the operating mechanism as it appears with the jack support stationary in a raised position.

Figure 2 is a fragmentary view of the parts as they appear in side elevation with the handle starting downward on a jack lowering stroke.

Figure 3 is a fragmentary detail view taken in section through the handle on the line 3—3 of Fig. 1.

Like parts are identified by the same reference characters throughout the several views.

The jack comprises a generally conventional arrangement in which the base 3 carries a standard 4 providing a guideway in which the toothed post 5 is vertically reciprocable to lift the load imposed on any one of the saddles 6, 7 or 8.

The standard 4 has the general form of a channel but is cut away at its rear upper portion to expose the teeth 9 of the post and to provide a cam surface 10 for actuating the lifting pawl 12. The lifting pawl comprises the central part of a yoke 15 suspended at its ends by bolts 16 from the short end of the handle lever 17. The handle lever is fulcrumed on a bolt 18 which extends through the ears carried by the jack column. Also pivoted on bolts 18, and disposed between the ears 19, is the holding pawl 20 which is normally thrust by spring 21 into engagement with one of the teeth of the jack post 5.

A control member 25 connected with holding pawl 20 extends along the lever 17 to the terminal handle portion 26 thereof and is there provided with some convenient finger operable connection such as the loop 27. An eye bolt or

the like at 28 on the lever 17 serves as a guide in which the control member 25, in this case a wire link, is supported and is permitted the necessary longitudinal movement and the slight degree of oscillatory movement required in the manipulation of the lever.

During the lifting operation of the jack it functions normally in accordance with conventional practice. The handle 17 is oscillated up and down. At each up stroke the lifting pawl 10 12 engages beneath a tooth of the post and lifts the post. When the post has been lifted for a distance corresponding to the stroke of the lever, the lever is oscillated upwardly and the tendency of the post to descend is checked by the holding 15 dog 20.

During the continued oscillation of the jack lever 17 the control member 25 is left free and will move relatively to the lever, reciprocating back and forth through the guide 28 as the lever 20 oscillates.

When it is desired to lower the jack the lever is lifted to substantially the position shown in Fig. 2, whereupon the control member 25 will have reciprocated through the guide into sufficiently close proximity to the operator's hand to be engaged by his forefinger as shown. With the operator holding the control member 25 in this position he lowers the handle from its Fig. 2 position, thus pulling the holding pawl 20 from the tooth 9 with which it is engaged to support the load. The withdrawal of the holding pawl from beneath this tooth drops the post 5 and the load sustained thereby on to the lifting pawl 12, and the handle is now permitted to swing upwardly under pressure of the post 5 to lower the load one tooth. In such upward movement of the lever the holding pawl 20 will, notwithstanding its retraction, be forced into the space below the next tooth of the post to receive the weight 40 of the post and the load imposed thereon when the lifting pawl 12 is ejected from engagement with the post by the cam surface 10. From this extreme position of the lever 17 the lever is now moved downwardly to the position shown in 45 Fig. 2 to repeat the cycle and lower the post another tooth, the operator's finger being used continuously to maintain the retracted position of the holding pawl 20.

Such a construction as that disclosed has the 50 merit of being extremely inexpensive and at the same time reliably effective to control the raising and lowering of the jack post with perfect safety to the operator notwithstanding the overhang of the body. But for the control member 25 the 55

operator would, to manipulate this type of jack, be obliged to reach under the vehicle to directly retract the holding pawl 20 with one hand while manipulating the lever 17 with the other hand 5 for the lowering operation.

I claim:

1. In a jack, the combination with a post, of a column in which said post is reciprocable, a lever pivoted to said column and provided with post 10 elevating means, a holding detent pivotally mounted on said column and engageable with said post for maintaining it in elevated positions, spring means providing a relatively fixed bias urging said detent toward said post, a link connected with said detent and extending along said 15 lever, and a guide for said link connected with said lever and in which said link is normally reciprocated by relative movement between detent and lever during the manipulation of said 20 lever for post elevation, said link comprising means for transmitting to said detent the same movement manually imparted to said lever, whereby said link is constrained to actuate said detent against said bias in the course of lever 25 movement for the lowering of said post.

2. In a device of the character described, the combination with a jack comprising a post, a column in which the post is reciprocable, and a holding detent for maintaining said post in an 30 elevated position, of a lever pivoted to said column and including means for post elevation therein and for lowering said post on retraction of said detent, said column including a cam surface engageable by said means in one position of said 35 lever for the displacement of said means to post releasing position, guide means carried by said lever at a point remote from said column, and a control member connected with said detent and extending along said lever through said guide 40 means, said detent being biased toward a position of engagement with said post whereby in the normal manipulation of said lever to raise the post said detent holds said control member and the guide means reciprocates thereon, said control 45 member having a terminal ring exposed adjacent the end of said lever for manipulation by the same hand with which the lever is manipulated, whereby the motion of the operator's hand in manipulating the lever may be concurrently transmitted to said control member for the manipulation of 50 said detent with said lever against its bias to release the post for lowering movement.

3. In a jack, the combination with a post provided with teeth and a column providing a guide-way for said post, of a lever pivoted to said column and provided with a lifting pawl engageable with successive teeth of the post, a detent dog pivoted with respect to said column and having a predetermined bias for engagement with successive teeth of said post, a wire control member pivotally connected with said dog and extending along said lever toward the end thereof remote 55

from said column, guide means in which said control member is reciprocable respecting said lever by relative movement between the dog and said lever in the lifting of the jack post, and a handle carried by said control member adjacent 5 the handle portion of said lever, whereby said control member is subject to manipulation concurrently with the manipulation of said lever by the operator's single hand to restrain said control member for movement with said lever, whereby 10 to retract said dog periodically against said bias to permit the lowering of said post.

4. In a jack, the combination with a post provided with teeth and a column providing a guide-way for said post, of a lever pivoted to the column and provided with a lifting pawl engageable with successive teeth of the post in the course of lever reciprocation, means engageable with said pawl in the movement of said lever in one direction for disengaging said pawl from the teeth of 20 the post, a dog pivoted with respect to the column and engageable with successive teeth of the post, a control member pivotally connected with said dog at a point spaced from said lever and extending thence along the lever toward the end 25 thereof remote from the column, guide means in which the control member is reciprocable respecting the lever in the course of lever operation, and means for holding the control member against reciprocation relative to said lever, whereby 30 during the manipulation of the lever the motion imparted by the operator's hand is transmitted to said detent dog for the retraction thereof from successive teeth of said post.

5. In a jack, the combination with a post provided with teeth and a column providing a guide-way for said post, of a lever pivoted to said column and provided remote from said column with a handle portion, a lifting dog connected with said lever and engageable with successive teeth of the post upon the reciprocation of the lever, means carried by said column for releasing said lifting dog from tooth engagement in a position of said lever adjacent its lower extreme, a detent dog pivoted with the respective column and engageable with successive teeth of the post, said detent dog being adapted to receive the support of the post when a post tooth is released by said pawl, a control member pivotally connected with said dog at a point spaced from the pivot of said lever and extending along said lever toward its handle portion, guide means in which the control member is reciprocable along said lever during the lifting of said post, and a handle carried by the control member adjacent the handle portion of the lever to be grasped by the same hand of the operator with which the lever is manipulated as a means of constraining the control member for movement with the lever, whereby to oscillate said detent dog in accordance with lever oscillation on 50 its pivot.

ADOLPH J. RICKER.
